LESTER L. CARTER, OF SAN FRANCISCO, CALIFORNIA, ASSIGNOR, BY MESNE ASSIGNMENTS, TO SHELL DEVELOPMENT COMPANY, OF SAN FRANCISCO, CALIFORNIA, A CORPORATION OF DELAWARE

GAS TRAP

Application filed May 21, 1927. Serial No. 193,178.

This invention relates to the oil-producing industry and it particularly relates to gas-traps.

In the oil-producing industry, oil, as it is taken from the well, has a certain natural gas content. This natural gas is of value and it is ordinary practice to separate it from the oil, piping it to a gasoline recovery plant, a storage tank, or a place of use. The oil as it comes from the well, sometimes contains sand which lodges in the gas-trap, soon partly filling it and considerably interfering with its operation.

It is an object of this invention to provide a gas-trap in which the sand may be periodically removed therefrom.

Another object of this invention is to provide a gas-trap in which the internal parts may be washed in order to remove sand therefrom.

Another object of my invention is to provide a gas-trap in which the body of solid particles collected in the lower part thereof is caused to move through the dumping outlet thereof by lubricating the walls which the body of solid particles engages. This manner of removing the body of solid particles does not cause agitation of the body, and does not cause it to mix with the liquid.

This object I accomplish by directing streams of lubricating fluid along the surfaces of the walls supporting the body of solid particles. This results in the body sliding downward through the dumping outlet.

A still further object of this invention is to provide a gas-trap in which the amount of sand collected therein may be readily ascertained so that the operator may know when it is a proper time to remove the sand therefrom.

Other objects and advantages of the invention will be made evident in the following description.

My invention may be best understood by reference to the accompanying drawings in which

Fig. 1 is a vertical section through a gas-trap.

Fig. 2 is a cross section taken as indicated by the line 2—2 of Fig. 1.

Fig. 3 is a fragmentary view partly in section taken as indicated by the line 3—3 of Fig. 1, showing a means for ascertaining the amount of sand which has collected in the gas-trap.

Fig. 4 is an enlarged section of the indicating means, this view being taken as indicated by the line 4—4 of Fig. 3.

Fig. 5 is a cross section taken on the line 5—5 of Fig. 4.

Fig. 6 is an enlarged fragmentary view partly sectioned showing the means for removing the sand from the lower end of the gas-trap.

Fig. 7 is a view taken as indicated by the line 7—7 of Fig. 6.

The form of the invention illustrated in the drawings has a shell 11 provided with a conical bottom 13 and a dished top 14, these parts cooperating to provide a separating chamber 15. Supported in the separating chamber 15 near the upper end thereof is a spreader in the form of a cone 17. The cone 17 is supported by brackets 18 which connect to the shell 11. An oil-gas inlet 20 is connected to the separating chamber 15 through the top 14. The oil-gas inlet 20 is adapted to deliver an oil-gas mixture onto a point 21 of the cone 17 so that the oil-gas mixture will be spread, thus exposing a large surface so that the gas may easily free itself from the oil.

A gas outlet 23 is provided for withdrawing from the separating chamber 15 the gas which has separated from the oil. The inner end of this gas outlet 23 is disposed inside the cone 17. A safety valve 24 is provided in the gas outlet 23 outside the shell 11 so that a pressure above the safe working pressure may not be produced in the separating chamber 15. Near the lower end of the separating chamber 15 is an oil outlet 26. The oil outlet 26 extends through the wall of the shell 11 and is provided with a control valve 27. The control valve 27 has an operating arm 28 to which a rod 29 is connected. The rod 29 extends upward from the operating arm 28 and is connected to an arm 30 of a control mechanism. The control mechanism also includes a shaft 32 to which the arm 30 is connected,

100

and an arm 33 inside the shell 11 which arm 33 supports a float 34. The purpose of the control mechanism is to maintain the oil in the separating chamber 15 substantially at a level indicated by the dotted line 35 of Fig. 1. The separating chamber 15 is provided with a sand outlet 37 which is connected to the lower part of the conical bottom 13.

As previously pointed out, the oil-gas mixture which is taken from the well very often carries particles of sand. Some of these particles of sand collect on the cone 17 and others accumulate in a body at the lower part of the separating chamber 15 as indicated by the dotted line 38 of Fig. 1.

My invention provides a means for washing the sand from the cone 17, this means being illustrated in Figs. 1 and 2. Placed in the upper part of the separating chamber 15, 20 concentric with the inner end of the oil-gas inlet 20 at the apex of the cone 17, is a sand-flushing ring or spray-ring 40, having downward-directed openings 41. Connected to the spray-ring 40 is a clean-liquid line 42 which 25 extends through the side of the shell 11 as illustrated in the drawings. This clean-liquid line 42 is connected by means of a fitting 43 to a main line 44, and it has a shut-off valve 45 which controls the flow of liquid there- 30 through. When it is desired to wash the surface of the cone 17, the valve 45 is opened and liquid under pressure is supplied to the spray-ring 40. This liquid is directed downward by the openings 42 onto the cone 17 so that 35 any sand particles located thereon are washed away, falling with the liquid to the bottom of the separating chamber 15. Although various liquids may be used for flushing the cone 17, I prefer to use a clean oil such as one 40 which has already been passed through the gas-trap.

My invention also provides a means for removing the body of sand 38 from the lower end of the separating chamber 15, this means 45 being illustrated in Figs. 1, 6 and 7. As a matter of information, when a body of sand forms in the lower part of a separating chamber of a gas-trap, it packs so tight that the mere opening of a valve will not be sufficient 50 to remove the sand from the gas-trap. My invention provides a means which will now be described and which is located in the sand outlet 37 of the gas-trap. Referring particularly to Figs. 1, 6, and 7, the numeral 50 re- 55 presents an agitating nozzle which is provided with a central passage 51. Placed below the agitating nozzle 50 is a gate-valve 52 which is closed at all times except when it is desired to remove the sand from the gas-trap. Con- 60 nected to the lower part of the gate-valve 52 is a T-fitting 53, which is connected to a sand draw-off pipe 54. Adverting to the agitating nozzle 50 it has an annular chamber 56 which surrounds the central passage 51, being sep- 65 arated therefrom by a wall. Connected to

the chamber 56 and also to the central passage 51 is a plurality of jets 57. As illustrated best in Figs. 6 and 7, these jets 57 are pointed upward and also substantially tangential with respect to the diameter of the central passage 51. These jets 57 are so extended that they will direct streams of fluid upward through the said outlet 37 into the body of sand 38 in the lower part of the separating chamber 15. As indicated in Fig. 6, 75 the streams of lubricating fluid are directed upward and somewhat tangentially along the surface of the cone 13 which is engaged by the body of sand. There is agitation in the mouth of the sand outlet 37, which causes this extreme lower portion of the body of sand 38 to pass into the sand outlet. The streams passing along the surface of the cone 13 provide a lubrication so that the entire body of sand 38 will drop downward and pass 80 through the sand outlet 38. The streams do not emerge from the upper surface of the body of sand. As soon as the body of sand starts to flow, the valve 60 is closed so that the streams of lubricating fluid are shut off. 85 It is only necessary to provide lubrication to start the body of sand flowing through the sand outlet 37. Fluid under pressure is supplied to the chamber 56 by means of a pipe 59 having a shut-off valve 60 and being connected to the main line 44 by the fitting 43. I have specified the medium for agitating the sand as a fluid. This has been done purposely 90 because the agitating medium may be in the form of a gas or in the form of a liquid. 100 However, I prefer to use a liquid since a liquid will serve as a good carrier to carry the sand through the central passage 51 after it has been loosened by agitation. To assist in removing the sand through the sand draw-off 105 pipe 54, I provide a wash nozzle 62 which extends into the T-fitting 53 and is used in the flushing of the sand draw-off pipe 54. The wash nozzle 62 has a shut-off valve 64 and is connected to a water spray pipe 65 and a 110 vertical pipe 66 by means of a fitting 67. The vertical pipe 66 has a shut-off valve 68 and is connected to the fitting 43. The purpose of this arrangement is to permit either the liquid supplied by the main line 44 or a separate liquid spray through the pipe 65 to be used for flushing the sand through the sand draw-off 115 pipe 54.

This invention also, as previously mentioned, provides a means for ascertaining the amount of sand which has collected in the separating chamber 15. This part of the invention is illustrated best in Figs. 3 to 5 inclusive. Attached to the side of the shell 11 near the lower end thereof is an housing 70 which rotatably supports a shaft 71, this shaft 71 extending to the exterior through a pair of stuffing boxes 72. Connected to the shaft 71 inside the housing 70 is an arm 74 having a spherical enlargement 75 located 120

at the swinging end thereof. This arm 74 extends almost entirely across the separating chamber 15. Connected to the extending ends of the shaft 71 is a yoke 77 which carries a balance weight 78 whose function is to counter-balance the weight of the arm 74. Attached to one end of the shaft 71 on the exterior of the housing 70 is an operating lever 79 by means of which the arm 74 may be 10 swung from full line position in Fig. 3 into a position indicated by dotted lines 80. Supported adjacent to the lever 79 is a graduation-plate 81 having graduations 82. The purpose of this arrangement is to indicate to 15 the operator the position of the enlargement 75 in the separating chamber 15. When it is desired to know how much of a body of sand has collected in the separating chamber 15, the operator manually engages the operating lever 79 which is in the position shown 20 in full lines in Fig. 3, and moves it upward and outward until he can move it no farther. The movement of the operating lever 79 is arrested by engagement of the enlargement 25 75 with the surface of the body of sand 38. Broken line 83 represents the position of the parts of the indicating apparatus when the enlargement 75 has been made to engage the upper surface of the body of sand 38. The 30 operator will then note the graduation 82 which is adjacent to the operating lever 79 and he will know substantially how much sand has collected in the separating chamber 15. When a substantial amount has collected 35 he will set the sand removing means into operation and remove the body of sand from the gas-trap.

From the foregoing description it will be apparent that the gas-trap of this invention 40 is designed so that all sand may be readily removed from the separating chamber without a great deal of trouble and without a material loss of time. The feature of flushing the cone 17 is important inasmuch as it removes an encumbrance from the surface of 45 the cone. The means for removing the body of sand from the lower part of the separating chamber 15 is important to the invention because it efficiently removes the body of sand 50 in a very short time. Not only does the means serve to loosen the body of sand in the separating chamber 15, but it also serves to carry it away. The feature of lubricating the surface which supports the body of 55 sand in order to cause it to pass downward through the sand outlet, is extremely important to the invention. The decided advantage resulting from this feature is that the body of sand is not agitated on its surface; therefore the sand will not be mixed 60 with the oil. This precludes all possibility of the sand remixing with the oil and being carried through the oil outlet 26. The means for determining the level of the sand in the 65 separating space is important inasmuch as it

provides a way of ascertaining when the sand removing means should be utilized. Without this the operator would have to rely on guesswork which obviously is unsatisfactory.

It will be understood, of course, that I have 70 shown only a preferred form of the invention and that various modifications and alterations may be made on the design shown without departing from the spirit and scope 75 of the invention as defined in the appended claims.

I claim as my invention:

1. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the 80 bottom of said separating chamber; and means for directing streams of fluid tangentially inwardly into the space enclosed by said inclined wall and said solid-particle outlet so that any particles collecting at the 85 bottom of said separating chamber will drop through said solid particle outlet.

2. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the 90 bottom of said separating chamber; and means for directing tangential streams along said inclined bottom for lubricating said inclined bottom-wall so that any particles collecting at the bottom of said separating chamber will drop through said solid-particle outlet. 95

3. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the 100 bottom of said separating chamber; and means located in said solid-particle outlet for directing tangential streams along said inclined bottom for lubricating said inclined bottom-wall so that any particles collecting at the bottom of said separating chamber 105 will drop through said solid-particle outlet. 110

4. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the 120 bottom of said separating chamber; and 125

means for directing streams upwardly along said inclined bottom for lubricating said inclined bottom-wall so that any particles collecting at the bottom of said separating chamber will drop through said solid-particle outlet.

5. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the bottom of said separating chamber; and a nozzle surrounding a portion of said solid-particle outlet, said nozzle including an annular chamber, and upwardly pointed ducts connected to said annular chamber and said solid-particle outlet.

6. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the bottom of said separating chamber; and a nozzle surrounding a portion of said solid-particle outlet, said nozzle including an annular chamber, and upwardly pointed tangential ducts connected to said annular chamber and said solid-particle outlet.

7. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the bottom of said separating chamber; and a nozzle surrounding a portion of said solid-particle outlet, said nozzle including an annular chamber, and upwardly pointed ducts connected to said annular chamber and said solid-particle outlet, said ducts being positioned to deliver streams along said inclined bottom-wall.

8. In a device of the character described, the combination of: a shell providing a separating chamber, said shell having an inclined bottom-wall; means for introducing a liquid carrying solid particles, said solid particles dropping to the bottom of said separating chamber; a liquid outlet for said separating chamber; a solid-particle outlet at the bottom of said separating chamber; and a nozzle surrounding a portion of said solid-particle outlet, said nozzle including an annular chamber, and upwardly pointed tangential ducts connected to said annular chamber and said solid-particle outlet, said ducts being posi-

tioned to deliver streams along said inclined bottom-wall.

9. In a device of the character described, the combination of: a shell forming a separating chamber; a spreader in said separating chamber; inlet-means for introducing into said separating chamber a liquid carrying solid particles, said liquid contacting said spreader; means for cleaning said spreader; a liquid outlet for said separating chamber; and a solid-particle outlet for said separating chamber.

10. In a device of the character described, the combination of: a shell forming a separating chamber; a spreader in said separating chamber; inlet-means for introducing into said separating chamber a liquid carrying solid particles, said liquid contacting said spreader; means for directing into contact with said spreader, a fluid under pressure for cleaning said spreader; a liquid outlet for said separating chamber; and a solid-particle outlet for said separating chamber.

11. In a device of the character described, the combination of: a shell forming a separating chamber; a cone-spreader in said separating chamber; inlet means for introducing into said separating chamber a liquid carrying solid particles, said liquid contacting said spreader; a spray-ring above said cone-spreader for directing cleaning jets of fluid against said cone-spreader; a liquid outlet for said separating chamber; and a solid-particle outlet for said separating chamber.

12. In a device of the character described, the combination of: a shell providing a separating chamber; an inlet for said separating chamber; a liquid outlet; a solid-particle outlet in the bottom of said separating chamber; an indicating arm arranged for indicating the level of solid particles in the bottom of said separating chamber; and means for normally holding said indicating arm in non-indicating position.

13. In a device of the character described, the combination of: a shell providing a separating chamber; an inlet for said separating chamber; a liquid outlet; a solid-particle outlet in the bottom of said separating chamber; an indicating arm pivoted inside of said shell, said indicating arm being swingable so as to contact the surface of a body of solid particles in the bottom of said separating chamber; means for indicating the position of said indicating arm; and means for normally holding said indicating arm in non-indicating position.

14. In a device of the character described, the combination of: a shell providing a separating chamber; an inlet for said separating chamber; a liquid outlet; a solid-particle outlet in the bottom of said separating chamber; an indicating arm pivoted inside said shell, said indicating arm being swingable so as to contact the surface of a body of solid par-

ticles in the bottom of said separating chamber; means for indicating the position of said indicating arm; and means situated outside said shell for normally holding said indicating arm in non-indicating position.

5 15. In a device of the character described, the combination of: a shell providing a separating chamber; an inlet for said separating chamber; a liquid outlet; a solid-particle outlet in the bottom of said separating chamber; an indicating arm pivoted inside said shell, said indicating arm being swingable so as to contact the surface of a body of solid particles in the bottom of said separating chamber; means for indicating the position of said indicating arm; and a counterweight associated with said indicating arm for maintaining said arm in non-indicating position, said counterweight being located outside said shell.

20 16. In a device of the character described, the combination of: a shell providing a separating chamber; an inlet for said separating chamber; a liquid outlet; a solid-particle outlet in the bottom of said separating chamber; an indicating arm pivoted inside said shell, said indicating arm being swingable so as to contact the surface of a body of solid particles in the bottom of said separating chamber; means for indicating the position of said indicating arm; a counterweight associated with said indicating arm for maintaining said arm in non-indicating position, said counterweight being located outside said shell; and operating means associated with the pivoted end of said indicating arm for moving same into operating position.

25 30 35 In testimony whereof, I have hereunto set my hand at San Francisco, California, this 40 11th day of May, 1927.

LESTER L. CARTER.
